UNITED STATES PATENT OFFICE.

RICHARD J. GREENWAY, OF WESTERLY, RHODE ISLAND, ASSIGNOR TO C. B. COTTRELL & SONS COMPANY, OF STONINGTON, CONNECTICUT, A CORPORATION OF DELAWARE.

ANTIOFFSET MECHANISM FOR PRINTING PRESSES.

Application filed March 3, 1925. Serial No. 12,845.

The object of my invention is to provide certain improvements in the construction, form and arrangement of the several elements of the anti-offset mechanism whereby 5 the anti-offset powder may be efficiently and thoroughly applied to the freshly printed side of the sheet or web; said elements including a rotary carrier and a traveling endless belt having the same surface speed as 10 the carrier and arranged for contact (preferably extended contact) with the sheet or web while on the carrier, and a rotary perforated anti-offset powder containing roll being employed for applying the anti-offset 15 powder to the belt for transfer thereby onto the freshly printed side of the sheet or web, means being provided for vibrating the roll and for rotating it at a considerably lesser surface speed than the belt, to ensure the 20 proper distribution of the powder.

A practical embodiment of my invention is represented in the accompanying drawings, in which

Fig. 1 represents in side elevation so much 25 of a printing press as includes my improved anti-offset mechanism.

Fig. 2 represents a vertical section through the same.

Fig. 3 represents a detail cross section 30 taken in the plane of the line III—III of Fig. 1.

Fig. 4 represents a detail section taken in the plane of the line IV—IV of Fig. 3.

The rotary carrier is herein shown as a 35 sheet carrying cylinder 1, provided with sheet grippers 2, the shaft 3 of which cylinder is suitably mounted in the frame 4.

The endless belt 5 passes around the drive roll 6, the idler rolls 7 and 8 and the belt 40 tightener roll 9. These rolls are all suitably mounted in the frame 4 and the rolls 7 and 8 are so arranged as to cause the endless belt 5 to have an extended contact with the freshly printed side of the sheet on the carrier.

The rotary perforated anti-offset powder containing roll 10 has its shaft 11 suitably mounted in the frame 4, for both rotary and vibratory movement, said shaft having sleeves 12 and 13 resting upon rotary cams 45 14 and 15, carried by a shaft 16 driven from the shaft 17 of the drive roll 6 through the gears 30, 31 for imparting the vibratory

movement to said roll 10. The rotary movement is imparted to the said roll through the 55 geared connection 18, 19 between the shaft 11 and the drive roll shaft 17. This belt drive roll shaft 17 is driven from the rotary sheet carrier gear 20 through the gear 21, shaft 22, bevel gears 23, 24, shaft 25 and 60 bevel gears 26, 27.

The endless belt 5 and the rotary carrier 1 are driven at the same surface speed and the anti-offset powder containing roll 10 is driven at a lesser surface speed, in the present instance about one-eighth the speed of the belt.

The structure of the perforated anti-offset powder containing roll 10 is as follows:

The roll is provided with an annular series 70 of lengthwise elongated slots 28 covered by a fine mesh wire cloth 29 which is herein shown in the form of a cylinder inserted into the roll 10, it being understood however, that this wire cloth cylinder may be placed 75 either inside or outside of the roll, as desired.

It will be seen from the above description that I am enabled to distribute the anti-offset powder in the proper quantities onto the endless belt from the supply roll, said supply roll being driven at the proper speed relative to the speed of the belt and also being vibrated or agitated so as to ensure the proper distribution of the powder.

It is evident that various changes may be 85 resorted to in the construction, form and arrangement of the several parts without departing from the spirit and scope of my invention; hence, I do not intend to limit myself to the particular embodiment herein 90 shown and described, but

What I claim is:—

1. A rotary carrier for a freshly printed sheet or web, a traveling endless belt arranged for extended contact with the sheet 95 or web while on the carrier, and a rotary perforated anti-offset powder containing roll arranged in position to distribute the powder to the belt for transfer thereby onto the freshly printed exposed side of the sheet 100 or web.

2. A rotary carrier for a freshly printed sheet or web, a traveling endless belt arranged for extended contact with the sheet 105 or web while on the carrier, a rotary perforated anti-offset powder containing roll

arranged in position to distribute the powder to the belt for transfer thereby onto the freshly printed exposed side of the sheet or web, and means for driving the roll at 5 a lesser surface speed than the belt.

3. A rotary carrier for a freshly printed sheet or web, a traveling endless belt arranged for extended contact with the sheet or web while on the carrier, a rotary perforated anti-offset powder containing roll arranged in position to distribute the powder to the belt for transfer thereby onto the freshly printed exposed side of the sheet or web, and means for driving the carrier 10 and belt at the same surface speed and the roll at a lesser surface speed.

4. A rotary carrier for a freshly printed sheet or web, a traveling endless belt arranged for contact with the sheet or web 20 while on the carrier, a rotary perforated anti-offset powder containing roll arranged in position to distribute the powder onto the belt for transfer thereby onto the freshly printed exposed side of the sheet or web, 25 and means for vibrating the roll.

5. A rotary carrier for a freshly printed sheet or web, a traveling endless belt arranged for extended contact with the sheet or web while on the carrier, a rotary perforated anti-offset powder containing roll arranged in position to distribute the powder onto the belt for transfer thereby onto 30 the freshly printed exposed side of the sheet or web, and belt at the same surface speed and the powder containing roll at a lesser surface speed, and means for vibrating the said roll.

the freshly printed exposed side of the sheet or web, and means for vibrating the roll.

6. A rotary carrier for a freshly printed 35 sheet or web, a traveling endless belt arranged for contact with the sheet or web while on the carrier, a rotary perforated anti-offset powder containing roll arranged in position to distribute the powder onto 40 the belt for transfer thereby onto the freshly printed exposed side of the sheet or web, means for driving the carrier and belt at the same surface speed and the powder containing roll at a lesser surface speed, and 45 means for vibrating the said roll.

7. A rotary carrier for a freshly printed sheet or web, a traveling endless belt arranged for extended contact with the sheet or web while on the carrier, a rotary perforated anti-offset powder containing roll arranged in position to distribute the powder onto 50 the belt for transfer thereby onto the freshly printed exposed side of the sheet or web, means for driving the carrier 55 and belt at the same surface speed and the powder containing roll at a lesser surface speed, and means for vibrating the said roll.

In testimony, that I claim the foregoing 60 as my invention, I have signed my name this 27th day of February, A. D. 1925.

RICHARD J. GREENWAY.
